Application January 16, 1943, Serial No. 472,636

30 Claims. (Cl. 66—89)

1

My invention relates to novel knitted fabrics, to a new method of making them, and to improvements in straight or full-fashioned knitting machines.

The standard full-fashioned stockings are "two unit" stockings, that is, they are stockings made from flat blanks knitted on two machines, a legger, and a footer. The blank for a standard "two unit" stocking is begun on the legger and at the upper or welt end, i. e. the widest point, and comparatively narrower heel tabs are knitted at the outer edges of the leg, at the lower end. Advantage is taken of the transfer of the blank from the needles of the legger to those of the footer to spread the heel tabs outwardly, placing the originally inner edges of the heel tabs on the needles and thereby increasing, or widening the stocking at the heel. Consequently, when producing a stocking blank on the standard legger and footer machines it is not necessary to widen the fabric in the heel area, but in making "single unit" stockings it is necessary to widen the fabric in this area and this can be done by employing a special routine, involving stopping the machine and turning the end stops by hand, or by modifying the design of the machine so that loops may be added by automatic action during knitting. The latter solution is recognized as more desirable, but difficulty has been encountered in providing a mechanism adapted to make not only a satisfactory form of heel but also a non-ravelling selavage along the widened portion of the fabric.

In making flat-knitted blanks for stockings and socks on so-called "single unit knitting machines," it is necessary to widen the fabric at the upper heel as well as to narrow it at other places, for example, in the lower heel.

One object of my invention is to provide an automatic mechanism adapted to widen knitted fabric and to produce a non-ravel selavage along the widened section.

Further, the standard full-fashioned knitting machines are provided with comb carrying rods and end stops, together with threaded spindles for operating said rods and stops, two spindles at each end of the machine. A known mechanism for manipulating the spindles for the end stops and for the point comb rods of a full-fashioned knitting machine includes a pawl at each end of a machine, a so-called "back-racking pawl," for turning the spindle for the point comb rods one needle at a time in the widening direction during certain narrowings, as well as other pawls for turning both spindles at each end two needles at a time in the narrowing direction and in the widening direction.

2

Another object is to provide a novel automatic racking mechanism employing certain parts of said known mechanism for manipulating the end stop spindles and comb operating spindles of full-fashioned and other straight knitting machines to widen the fabric during knitting.

Another object is to provide a control arrangement for the narrowing and widening mechanism of a single unit knitting machine adapted to cause the back-racking pawls to act in the course of widening the fabric.

A further object is to utilize the pawls for back-racking to assist in widening the fabric when the end stops are between certain positions at which narrowing occurs without back-racking.

The end stops of straight knitting machines including full-fashioned machines are almost always moved two needles at a time so that the yarn carrier fingers will come to rest above dividers. Otherwise the sinkers would need to be modified. To make the desired selvage, however, the point comb rods must move only one needle at a time.

A still further object, therefore, is to provide means for moving the spindles for the point carrying rods two needles per revolution of the camshaft of the machine, but in two successive steps.

In seaming the widened heel areas of single unit full-fashioned stockings, it more or less frequently happens that the first one or two of the widening marks are not taken into the seam. I have found that by placing the first few marks of a widening line nearer the edge of the blank than the remainder, this difficulty is overcome.

Another object is to provide a single unit stocking blank having a novel widening line to facilitate taking the line entirely into the seam.

An additional object is to provide a single unit stocking blank having widening marks in ornamental or letter-shaped arrangement.

It is also an object to provide a novel method for widening flat knitted fabrics.

With these and other objects in view, which will appear as the description proceeds, my invention resides in the novel fabric, method of knitting, features of construction and arrangement of parts in cooperative relationship as hereinafter more particularly pointed out in the 50 claims.

Figs. 29, 30 and 31 are views similar to Fig. 28 showing several other steps in the operation of the narrowing head during the production of a stocking blank in accordance with the invention;

Fig. 32 is a view of a portion of the stocking blank shown in Fig. 2;

Fig. 33 is a top plan view of the control mechanism as positioned at the start of the stocking blank;

Figs. 34 to 40 are views similar to Fig. 16 with

the parts in different relative positions showing the step-by-step operation of the control mechanism during the production of the stocking blank of Fig. 32;

Fig. 41 is a view similar to a portion of Fig. 33 showing a further step during the production of another form of stocking blank of the invention;

Fig. 42 is an end view of the right end of the machine and showing the modified form of mechanism for controlling the operations of the pawls for the narrowing spindles; and

Fig. 43 is a top plan view of a portion of the mechanism shown in Fig. 23.

In the drawings and description, only the means necessary to a complete understanding of the invention have been specifically set forth; further information as to the construction and operation of other related, usual and well known knitting machine elements, mechanisms, etc., may be found in one or more of the following publications:

1. Pamphlet entitled "Full-Fashioned Knitting Machines," published and copyrighted by the Textile Machine Works, Reading, Pennsylvania, in 1920.

2. Three catalogs entitled "The 'Reading' Full-Fashioned Knitting Machine Parts Catalog," published and copyrighted by the Textile Machine Works, in 1929, 1935 and 1940, respectively.

3. Booklet entitled "The 'Reading' High-Production Full-Fashioned Knitting Machine," which forms a supplement to the above noted 1940 parts catalog of the Textile Machine Works, and which booklet is a publication of the Textile Machine Works, and was copyrighted by the latter in 1940.

4. Pamphlet entitled "Knitting Machine Lectures," published by the Wyomissing Polytechnic Institute, Wyomissing, Pennsylvania, in 1935.

I have shown in the drawings an embodiment of my apparatus invention adapted to operate in accordance with my method invention and to manufacture fabric in accordance with my article invention. As will appear more in detail hereinbelow, my apparatus not only involves a novel principle of operation in the knitting machine art in that it moves a cam piece for controlling an operating pawl out of its active position by a movement transverse to the path of its cooperating member, but it accomplishes the result of automatically maintaining a racking pawl inactive during operations for altering the width of the fabric in one direction while maintaining the same pawl active during operations for altering the width of the fabric in the opposite direction and, surprisingly, while the changes in one direction are within the same limits of width as those in the other direction.

Further, my apparatus invention involves a radically novel concept in that it is adapted to make lines of lace openings that initially incline toward the selvages when followed in the direction of knitting and then run parallel to widened selvages, thereby providing a stocking fabric of attractive and novel appearance as well as a fabric or loop arrangement capable of increasing the elasticity of the heel region as well as ornamenting it. The apparatus according to my invention further is remarkably flexible and adapted to produce a variety of fabric arrangements adapted to different purposes.

Referring to Figs. 1 and 2, I have shown a flat-knitted full-fashioned stocking A and a single unit blank B composed essentially of plain knitted loops and adapted to form, when the edges of

the blank have been seamed, the full-fashioned stocking A. Blank B comprises a welt W, a leg portion L, an ankle portion M and a foot portion F including heel portions H. The blank B is shown as narrowed at the knee and the calf to reduce the width to that desired for the angle. The method of narrowing is, of course, well known and so is mechanism suitable for the purpose. This invention has no contact with narrowing except in so far as the mechanism and method used for widening the fabric is related to the method and mechanism used for narrowing it.

As is evident from Fig. 1, the narrowing operations make the knee and calf fashion marks K and C, respectively. After the lower fashion marks produced by the leg or calf narrowings, an additional thread or additional threads is or are introduced into the blank to produce the heel reinforcements and such reinforcements are shown as extended throughout the heel and sole regions to the toe of the blank B. The upper portions of the heel are indicated at R and are known as the "high heel", overlapping from the foot to the lower ankle portions. Said portions R have parallel walewise sides as shown and will be understood to extend above the level of the heel of a low shoe, so that they are nowadays ordinarily visible. According to the preferred form of my fabric invention the high heel portions R have lace apertures therein arranged in a line P at an outward inclination to the wales and selvage edges of the high heels R so that, when the edges of the blank B are seamed together to form the stocking A, the portions of lines P in the high heel portions R come close together at the lower ends of the portions R to give the appearance of a V. The lines P, however, do not terminate at the lower edges of the high heel but extend farther down into the heel proper H for reasons that will presently appear. Shortly below the upper edges of the reinforced areas, immediately below the portions R, the blank must be widened to produce fabric for the heel pocket.

In Figs. 6, 7 and 8, I have shown three forms of fabric according to the present invention. In each of the fabrics shown in Figs. 6, 7 and 8, the first course to be widened by having the number of its loops increased has two loops more than the preceding adjacent course. In, by way of example, the production of said first course b in Fig. 7, having an increased number of loops, the two added loops are knitted into end loops of the preceding course a which have been transferred outward one needle, the yarn carrier being moved out two needles simultaneously. Then, as the yarn carrier has been moved out two needles, yarn is laid in the new and widened course by two additional and unoccupied needles, one at the side of the fabric at which the yarn carrier came to rest in the next preceding course and one needle at the other side of the fabric. The two needles, one on each side of the fabric, outside the ones to which the edge loops were transferred, to which yarn is fed in the course b do not, however, knit properly formed loops until after a second operation of spreading the edge loops outwardly as shown in course c. In the course b, the one following the first operation in which the edge loops were transferred outward and for several courses thereafter, the outer needles to which yarn is fed do not knit their loops, there being nothing through which the outer needles can draw the yarn. The needles therefore merely cause for a time, loose float yarns to form

at the edges of the fabric after the first outward transfer of the edge loops. In the fabric shown in Fig. 7, after the second outward transfer of edge loops, the one shown in course c, for 5 reasons not clear, a sinker loop e is formed at one side of the fabric outside the outer needle loop and in the next course after the sinker loop e has appeared, a sinker loop f is formed on the opposite edge of the fabric. In the next courses 10 following the appearance of each sinker loop e and f, a needle loop is formed outside the loops e and f as shown at g and h. By this time the fabric has been widened by two needle loops picked up in addition to those added by the outward transfer 15 of needle loops, in the act of knitting three or four courses, two by transferring out the edge loops and two which were picked up due to stepping out the carrier two needles. From this point onward, I am able to add four loops on 20 the average for each widening operation, although the number of courses required for adding two loops at each side of the fabric is not uniform. As shown, however, three courses are used per repeat in each of the first three operations 25 in which the edge loops are transferred outwardly and four courses are used in the repeat of the fourth such operation. The fabric shown in Fig. 8 also developed sinker loops and then needle loops in addition to those added due 30 to the outward transferring operations in the same sequence as that shown in Fig. 7.

In the fabric shown in Fig. 6, however, a somewhat different effect was produced although the overall result was the same. In Fig. 6, as in Figs. 35 7 and 8, only one loop was added at each edge of the fabric in the course b by the first stepping out operation, but in Fig. 6, immediately after the second stepping out operation, a needle loop x and accompanying sinker loop u were 40 formed at the right hand selvage, a sinker loop e only having been formed in the same course as loop x at the left selvage. In the succeeding course, the sinker loop e grew into a needle loop with accompanying sinker loop at the left selvage so that the difference between the fabric of 45 Fig. 6 and those of Figs. 7 and 8, so far as the addition of loops was concerned, was the appearance of an additional needle loop at the same side and in the same course as an additional sinker loop instead in a succeeding course and a course sooner than sinker loop f. Ordinarily it does not happen that both an additional sinker loop and an additional needle loop build on in the same course. It will be understood that the 50 fabrics shown in Figs. 6, 7 and 8 were made on the same machine as the fabrics shown in Figs. 1 and 2, but that the lace openings in the courses prior to the beginning of the operations for widening the heel are omitted in Figs. 6, 7 and 8. 55 In the portions of blanks shown in Figs. 4 and 5, the selvages along the widened sections of the fabrics, the heel portions, similarly to Fig. 2, are of locked character. The fabrics shown in Figs. 6, 7 and 8 are, however, different as regards the 60 positions of the lace openings formed at the times of the outward transfer of the edge loops. 65 In Fig. 7, the first two lace openings on each side of the fabric are only one needle wale from the selvage, the following lace openings being each two needle wales from the selvage. In the fabric of Fig. 8, the pair of lace openings in the first course and all other courses having such openings are spaced from the selvages each by two needle wales. In Fig. 6, the lace openings in the first course to have such openings are each 70 75

three needle wales from the nearest selvage and the lace openings in each of the remaining courses having such openings are each intended to be three needle wales from the nearest selvage, although only two needle wales are shown following the first, due no doubt to a failure of the mechanism to pick up two loops at each side of the fabric on the second widening operation.

The different spacings of the lace openings shown for the different fabrics have different purposes or objects. In the fabric of the blank B and stocking A shown in Figs. 1 and 2, it is not desired to take the lace openings along the widened portion of the heel into the seam. By leaving the lace openings out of the seam, a certain elasticity is imparted to the region of the heel and also the lines of the sides of the V in the high heel are continued down into the heel pocket, giving a more pleasing appearance to the heel when the stocking is examined on the sales counter. In the arrangement shown in Figs. 1 and 2, I therefore prefer to space the lace openings in the lines P of Fig. 2 about five or a sufficient number of needle loops from the selvages in the widened portions of the heel pockets H, so that the seam may be conveniently run outside the line of lace openings, giving the effect shown in Fig. 1. The arrangement shown in Figs. 1 and 2 is that preferred by me.

At times, however, it is desired to omit the V effect of Fig. 1 and also to take the lace openings into the seam. A blank Z having a line of lace openings Y close enough to the selvedges to permit this is shown on Fig. 4. Experience has shown, however, that, when this is attempted, the seamstress often misses the first lace opening or so in the vicinity of the angle between the high heel and the heel pocket. I have found that such mischance is much less apt to happen if the upper ends of the lines S of lace openings start a little closer to the selvedges as shown at J in a blank X shown in Fig. 5. It has been found desirable in this case to cause the lower ends of the lines of fashion marks C of the leg narrowings to bend toward selvedges of the blank as shown at D in Fig. 5. A stocking Q which may be formed from either blank Z or blank X is shown in Fig. 3. In each of Figs. 2, 4 and 5, lines T of fashion marks are shown formed by operations for narrowing the heel portions H, as well as lines U of fashion marks formed by operations for narrowing the toe parts of the blanks B, Z and X. Mechanism for forming the lines of fashion marks, K, C, T and U for forming the lines P, Y and S of lace openings and for causing the fashion marks C and lace openings S to bend for the desired short distances is shown in the drawings and described hereinbelow. It will be seen from Fig. 5, however, that the lower ends of fashion marks C are farther from the selavage edges than the upper ends of lines S. It is necessary, therefore, that the attendants shift the points by hand intermediate the lower ends of fashion marks C and the upper ends of lines S of lace openings in Fig. 5.

However, I do not limit myself in all cases to either leaving the lace openings out of the seams in the widened sections of the heel or to making bends in the lines of lace openings.

I have disclosed my apparatus invention in connection with a full-fashioned knitting machine of the single unit type, shown in Figs. 9 to 27 inclusive, but it will be understood that such application of the invention is merely illustrative.

Said machine includes a needle bar and means

to operate it to produce a succession of knitted courses, end stops and operating spindles therefor, point comb bars and operating spindles therefor, and pawl and ratchet means for operating said spindles in either direction, two pawls of said means cooperating to turn a spindle for the point comb bars two needles per revolution but in two steps of one needle each. The machine shown in the drawings comprises further a frame 10 55 including transverse end frames 56 and center frames 57 in parallel arrangement and connected by longitudinal members adapted to hold the end and center frames rigidly in place. On said frame 55 are mounted a variety of mechanisms including said means for knitting loops of yarn in successive courses, said knitting means being divided into sections of which there may be up to thirty, or more.

The knitting sections

20 Each knitting section of the usual full-fashioned knitter includes a needle bar 58, as shown in Figs. 28 to 31, having beard type needles 59 thereon, and other cooperating knitting elements, not shown, for forming loops on the needles from 25 yarn laid to the needles, and means including a main camshaft 62 to repeatedly carry the needle bar through a cycle of movements to knit, with the assistance to said cooperating elements, the loops of one course to those of the preceding course. Generally, a known arrangement called a couloring means moves a yarn carrying means to lay yarn to the needles of all the knitting sections simultaneously.

The camshaft and patterning means

Said means for knitting including the couloring means are operated from and, in a sense, include the longitudinally shiftable main camshaft 40 62, the cams on which operate the different means or mechanisms. As certain mechanisms of the machine operate only part of the time and others operate differently at different positions of the camshaft, a patterning means 63, shown in Fig. 45 9, is provided for determining which mechanisms shall receive impulses from the cams on the main camshaft in any given revolution thereof and when the camshaft is to be shifted.

Each mechanism receives its impulse from a 50 cam on the main camshaft through a cam follower. Generally speaking said cam followers may each be shifted in the direction longitudinally of the camshaft so as to be operatively engaged by a cam or disengaged therefrom. The shifting of said cam followers is accomplished in 55 most cases by rods operated, either directly or indirectly by a pattern chain 64 forming part of said patterning means 63. For this purpose, the pattern chain 64 is stepped, usually once every revolution, by a means (not shown) which is preferable of a known type and actuated by a cam on said main camshaft. A series of levers, one of which is shown at 66, is placed near the usual driving sprocket wheel for said chain and each may be turned through an angle at a desired 60 time to operate one of said rods to shift a cam follower directly or to set in motion a mechanism for so doing, thereby controlling the action of a given mechanism. The individual levers 66 are operated at desired times by buttons 67 which are clamped in use to links of the pattern chain in such position as to strike each a given lever at a given revolution of the cam shaft. Further, said chain controls the shifting of the camshaft 65 70 itself. To this end, a position is provided on the 75

chain for a button which throws into action a means (not shown) for forcing a roller on a transverse shaft 68 rearwardly into engagement with a lateral face of a cam 69 on the camshaft, causing the shaft to shift to the right as viewed from the front of the machine. Later in the same revolution the said roller engages a lateral face on another cam 71 on the camshaft 62 causing the camshaft to shift to the left to its original position. A spring 72 restores the shaft 69 to its original position as soon as the button 67 which caused it to be shifted has been moved out of active position by chain 64. Further, a position is provided in the pattern means for a button actuated lever (not shown) acting to stop the machine.

The left hand position of the main camshaft as viewed from the front of the machine is the knitting position while the right position of the camshaft is the one in which narrowing and widening operations occur and which is ordinarily called the "narrowing" position. The needles and other mechanisms are operated in both positions of the camshaft but have different movements in one than in the other, requiring different cams. The camshaft therefore is provided with both knitting cams and narrowing cams for the needles and said other mechanisms and the longitudinal movements of the camshaft determined by the pattern means automatically shift the relative positions of the cams and cam followers for causing the needle motions and for operating said other mechanisms from the knitting to the narrowing cams and back. The cam followers for the needle motions and for said other mechanisms therefore do not in general need to be controlled from the patterning means.

Narrowing machine

The knitting of a two machine type full-fashioned stocking or like blank, ordinarily called a standard blank, is begun at its wide end and all changes in width during manufacture are of a narrowing character, so that an important part of the mechanism in a full-fashioned knitting machine for changing the width of the fabric during knitting is called the "narrowing machine." Said narrowing machine comprises arms 73, shown in Fig. 9, extending forward from pivots at their rear ends on a longitudinal shaft 74 known as the back narrowing shaft. Said arms extend above the machine and support a front narrowing shaft 75 at their front ends. Said front narrowing shaft supports brackets 76 in which are slidably supported narrowing rods 77 to which are fixed point combs 78 carrying groups of narrowing points 79 for narrowing and widening the fabric. Part of the weight of said arms as well as the weight of the front narrowing shaft and parts thereon is supported by links such as 81 pivoted at their upper ends to said shaft 75 and, at their lower ends, to oscillatable levers such as 82 (Fig. 9) which are pivotally mounted in the frame to oscillate about axes at their front ends and have cam followers such as 83 journaled thereon, the cam followers resting on round cam disks 84 on the main cam shaft when the shaft is in its left or knitting position to support links 81. In a narrowing or widening operation, the camshaft is shifted so that the cam followers 83 on said levers 82 are above cams 86 shaped to lower the points of the combs into contact with the needles. The combs having been properly set, one or more loops at the edges of the fabric are thereupon picked off the needles

by the points. Said lowering cams then raise the points so that they just clear the needles and knockover bits, and the sinkers and dividers (not shown) having been retracted, the narrowing rods 77 are then shifted to move the combs. The lowering cams 86 then again lower the points into contact with the needles so that the loops on the points also surround needles and the points and needles go down and, the cooperating retractable knitting elements having been advanced again, the lowering cams raise the narrowing machine so that the loops are stripped off the points and remain on the needles in a transferred position, the camshaft thereupon being shifted back to the left or knitting position. The point combs 78 remain in the position to which they moved in the transferring operation until again actuated. The fabric is thereby narrowed or widened, as the case may be, depending on the direction in which the combs were moved. The drive for the couloring means being disconnected during the period of the main camshaft is in shifted position, of course, no yarn is laid to the needles during a narrowing or widening operation.

Narrowing heads

Means for moving rod 77 and thereby the combs 78 are mounted at the ends of the machines and form parts of what are known as narrowing heads 87. The narrowing heads each include two spindles, one 88 (Figs. 9 and 10) for moving the narrowing rods 77 and the other spindle 89 for moving the end stops 91 which limit the traverse of the carrier rods 92 for the thread guide fingers 90 as shown in Figs. 28 to 31, so as to determine the number of needles to which thread will be laid for knitting. For producing the motions just mentioned of the narrowing rods and end stops, respectively, the spindles 88 have each two reversely threaded portions 93 on each of which is a nut 94, while each spindle 89 has a threaded portion on which is a nut 96 on which is mounted the end stops 91 for limiting the travel of the yarn carriers. It is desirable that the spindles for the end stops 91 be moved two needles at a time because of the relationship of the yarn carriers with the sinkers and the dividers. In case the combs 78 are moved only one needle, the inner points 79 on the combs, if the combs overlap the selvages, will make lines of fashion marks or lace openings inclined to the selvages. If this is not desired, the combs must be moved two needles at a time or the combs must be given a second step of one needle to restore their relative position with respect to the end stops.

For turning the spindles of the narrowing heads of full-fashioned knitting machines, a mechanism has been shown which contains many known features comprising an actuator 97, best shown perhaps in Fig. 10, at each end of the machine which is raised and lowered by a cam 38 on the main camshaft 62 whenever a cam follower 99 for the actuator is brought into active position because of a shift of main camshaft 62 to the right, when viewed as in Fig. 9, in carrying out a narrowing or a widening operation. Pawls 101 and 102, Fig. 19, are actuated by the actuator 97, but directly mounted on levers 103 and 104 journaled on spindles 88 and 89, Figs. 10 and 19, and are arranged to act on suitable ratchet wheels to turn both the spindles 88 and 89 two needles in the narrowing direction for narrowing during the knitting of a stocking blank. In the arrangement shown, two other pawls 105 and

11

106 are mounted on the actuator 97 and arranged to act on suitable ratchet wheels to turn both the spindles 88 and 89 in the widening direction. In the arrangement shown and perhaps most clear from Fig. 19, a bracket piece 107 is bolted to the actuator 97 at points E and G while pawls 105 and 106 are pivoted to piece 107 at points O and V, respectively. However, it is obvious that the actuator 97 may be so shaped, if desired, that the pawls 105 and 106 may be pivoted directly on the actuator without any intervening piece. Means are provided also, as hereinafter described in detail whereby the action of widening pawl 105 on spindle 88 may be modified to produce only a one needle movement although the amplitude of the movement of actuator 97 is sufficient to cause both pawls 105 and 106 to always produce two needle movements of spindles 88 and 89. In the arrangement shown in Fig. 10, spindle 89, when actuated, is always turned enough to produce a movement along the axis of the spindle equal to twice the distance between two adjacent needles although means is provided for preventing pawl 106 from acting at times when the actuator 97 is reciprocated. Mounting the widening pawls on the actuator 97 instead of on levers 103 and 104 as heretofore, especially pawl 105 for the comb spindle 88, results in racking the spindles on the upstroke of actuator 97 when widening instead of on the downstroke thereof. This has important practical consequences as will presently appear. The machine also has a usual back-racking pawl 109 of the pull-back type on the actuator which is automatically controlled to turn the comb moving or narrowing spindle one needle in the widening direction. Such one needle movement of the narrowing spindle in the widening direction is commonly employed during the heel narrowing operation after each two needle movement of the spindles in the narrowing direction. As pointed out more fully hereinbelow, I have found a new use for the back-racking pawl in connection with widening the fabric. Means are known whereby the pawls for causing narrowing movements of the spindles or the pawls for causing the widening movements are controlled from the pattern chain. In the arrangement shown, springs are provided which bias the pawls toward their active positions and a cam means is provided having a cam member pivoted on one of the spindles and adapted to throw at one time the narrowing pawls and at another time the widening pawls out of action in response to the action of the pattern chain, the widening pawls or the narrowing pawls being permitted, at the same time, to move into active position. I have shown a modification of said known means according to my invention having a pattern controlled cam means including cams such as 108 pivoted one on each of the point comb spindles which acts directly on the two of the pawls for such spindle which move it at times two needles, the two corresponding pawls for the end stop spindle 89 being connected by links to those directly controlled by the cam 108 so as to move the same way, whereby said pivoted cam controls the pawls for both spindles and moves them all simultaneously, all the pawls that is, except the back-racking pawls 109. Of course, an equivalent means for controlling four pawls, two on each spindle, would be one having a control cam journaled on each spindle, one such cam being directly controlled by the pattern means.

Said four pawls for operating spindles 88 and 89

75

12

89, in addition to back-racking pawl 109, are 101, 102, 105 and 106. Pawls 101 and 102 act respectively on ratchet wheels 111 and 112, Figs. 19 and 21, on spindles 88 and 89, respectively, and 5 serve to turn spindles 88 and 89 in the direction to narrow the fabric, while pawls 105 and 106 act on ratchets 113 and 114 respectively which are fixed to shafts 88 and 89 respectively. Pawls 105 and 106 serve with ratchets 113 and 114 to turn spindles 88 and 89 in the widening direction. All 10 four pawls 101, 102, 105 and 106 at each end of the machine act on the upstroke of actuator 97, back-racking pawl 109 being the only one of the pawls shown which acts on the downstroke of the actuator. The pawls 101 and 102 are shown 15 as connected by a link 115 so that when cam member 108 moves pawl 101 away from its ratchet wheel by acting on a transverse pin 116, in Fig. 19, fixed to the pawl, link 115 draws pawl 102 20 out of operative relation to its ratchet at the same time. Similarly, pawl 105 is connected to pawl 106 by a link 117 so that, when cam 108 is turned to throw pawl 105 away from its ratchet 25 113 by acting on a pin 118 fixed to the pawl, pawl 106 is moved away from its ratchet 114 at the same time. Cam 108 is so formed that it throws out of action either pawls 105 and 106 or pawls 101 and 102, depending on the position of the cam 108. The means for turning swinging cam piece 30 or part 108 from one position to the other includes, in addition to the chain 64, a circular disk 119 on camshaft 62 and a cam 121 alongside disk 119. Also, a roller type cam follower 122 or its equivalent is provided which is journaled in a 35 lever 123 which is connected to a pivoted shaft 124 (Fig. 10), in this instance at the rear of the machine frame. Shaft 124 has fixed thereon also a lever 125 which extends forwardly from shaft 124 and has a rod or link 126 pivoted thereto 40 which extends upwardly and somewhat rearwardly from a point at or near the front end of lever 125 as shown at 127 to a pivotal connection with the cam 108 at 128. Therefore, if cam follower 122 remains on round or circular cam disk 45 119 as shown in Fig. 10, cam 108 remains stationary in the position shown in Fig. 10 and the narrowing pawls 101 and 102 remain in active position. If, however, cam 121 is moved over to align it with follower 122 the lever 125 is lowered 50 from the position shown in Fig. 10 to that shown in Fig. 19 and cam 108 is swung at the same time by link 126 so that narrowing pawls 101 and 102 are pushed back from their ratchets during the time the actuator 97 is being raised by its cam 55 98 while widening pawls 105 and 106 are permitted to drop into contact with their ratchets 113 and 114 during a portion of a revolution so as to turn spindles 88 and 89 in the widening direction on the upstroke of the actuator 97.

60 For controlling link 126 to swing cam 108 to permit a widening operation, a mechanism 129 is provided, best shown, perhaps, in Figs. 9 and 20. Mechanism 129 is shown as largely mounted on a standard 131 shown as fixed to the front beam of the machine frame 55. The upper end of standard 131 is bifurcated to provide a pair of arms 132 and 133 at its upper end in which is slidably mounted a bar or rod 134 for endwise movement longitudinally of the machine. A collar 135 is fixed to bar 134 and arranged to contact the inner face of arm 132 to limit the movement of bar 134 to the left while an elongated collar 136 is fixed to bar 134 and arranged to contact the inner face of arm 133 to limit the 65 movement of the bar to the right. Collar 136

is shown in Fig. 19 as extending downwardly and somewhat forwardly from bar 134 and as having a notch 137 in its lower end through which extends a pin 138 which is fixed in arm 133 and serves to keep collar 136 and bar 134 from turning. Fixed on bar 134 is a vertically extending support 139 having a set screw in its upper end whereby its effective height may be adjusted. Also fixed to bar 134 is a collar 141 having a pin 142 projecting forwardly therefrom. A lever 143 pivoted on standard 131 at 144 cooperates with pin 142 at times to throw bar 134 to the right into the position shown in Fig. 20. Lever 143 is operated from the pattern chain 64 at predetermined intervals by a rod 146. Except at the times it is acted on by chain 64 through one of the levers 66 of pattern means 63, the end of rod 146 is held toward the right as viewed in Figs. 9 and 20 by a spring 147 (Fig. 9) connected between a point on the rod and a point on the frame 55. Therefore, lever 143 stands, normally, in the position shown in Fig. 9 with its upper end free of the pin 142. A spring 148 (Fig. 20) connected at one end to bar 134 through collar 136, or otherwise, and at its other end to arm 132 serves normally to hold bar 134 to the left as viewed in Figs. 9 and 20. As shown in Figs. 9 and 10, when bar 134 is at the left, part 139 on bar 134 is directly beneath the lever 123 and supports it independently of round disk 119 and follower 122, collar 135 being so set that spring 148 cannot move bar 134 so that part 139 will pass to the left of the plane of lever 123, as viewed in Figs. 9 and 20. However, when chain 64 acts to throw the parts into the position shown in Fig. 20, lever 123 is free to drop, so far as part 139 is concerned. Therefore, the mechanism 129 may serve as a discriminating means whereby cam 108 can cause spindles 88 and 89 to move in either the widening or the narrowing direction. Although the camshaft 62 shifts to the right for both the widening and narrowing operations, no button for operating rod 146 is placed on chain 64 for courses to be narrowed. Therefore, although the shift of shaft 62 to the right at such times carries round disk 119 out from under follower 122, it cannot drop onto cam 121 because part 139 remains under lever 123. Therefore cam 108 remains in the position shown in Fig. 10 and the narrowing pawls act on the spindles. When widening is to be performed, however, a button is placed on chain 64 to move rod 146, bar 134 and support 139 each time the shaft 62 is shifted, whereby the lever 123 is lowered and raised again by cam 121 to thereby operate shaft 124, lever 125 and link 126 to turn cam 108 into the position shown in Fig. 19 in which the widening pawls are active.

In Figs. 10 and 19, the shaft 124 is shown as journaled at the rear of the machine. This, however, is optional and in Figs. 42 and 43 I have shown a mechanism 149 for controlling the position of cam 108 comprising a shaft 151 which is at the front of the machine and has a cam lever 145 secured thereto cooperating with the cam 121 and associated disk 119 in a manner similar to the lever 123. The shaft 151 also carries a lever 150 which is connected to the link 126 to turn the cam 108 in the same manner as hereinbefore set forth. Otherwise, the mechanism 149 is the same as mechanism 129 having the same number of parts of the same shape and similarly arranged except as to changes incidental to placing the shaft 151 at the front of the machine. Figs. 42 and 43, therefore, are not further described herein.

However, it is desired that during widening operations pawl 105 turn the narrowing spindle 88 only one needle while it is desired that pawl 106 turn the end stop spindle 89 two needles, the usual distance. Therefore, pawl 106 is permitted to act on ratchet 114 without hindrance while pawl 105 is prevented from turning spindle 88 more than one needle. For the purpose of limiting the action of pawl 105 in widening operations, 10 a cam piece 152 is adjustably mounted on spindle 88 near the end of the spindle and provided with an upward extension 153 having arcuate slots 154 therein through which screws 155 are inserted into a fixed block 156 (Fig. 9) immediately behind slots 154. The heads of screws 155 are adapted to bear against cam 152 so that it stays in the position in which it is set by the operator and cam 152 is so shaped that, when set as in Fig. 19, it bears against the edge of pawl 105 20 to hold it away from ratchet wheel 113 until after actuator 97 has started up from its lowest position, so that pawl 105 catches the ratchet 113 only in time to turn the ratchet enough to move the narrowing combs a distance of one needle. 25 The edge loops are therefore transferred outward one needle at each widening operation when member 152 is in the position shown in Fig. 19 and in which the screws 155 are at the front ends of the slots 154. By swinging member 152 clockwise as viewed in Fig. 19 until the screws 155 are at the rear ends of slots 154, the pawl 105 will be permitted to turn spindle 88 two needles, so that spindle 88 may keep step with spindle 89 when desired. In order that spindle 89 may not lag behind the spindle 88 in the heel widening operations and thereby throw the combs out of position relatively to the selvage and the end stops, the spindles 88 are turned enough to move the combs another one needle distance during 30 the same revolution in which the edge loops were stepped out. This is done by the back-racking pawl 109, as will now be described. 35

A special arrangement is provided according to this invention for controlling the back-racking pawl which holds the pawl inactive or permits it to act, partly according to the position of the end stops and partly according to the direction of movement of the end stops. Each back-racking pawl 109 is pivoted to the reciprocating actuator 97 at its end of the machine near the central longitudinal plane of the machine so as to extend up between the two threaded spindles 88 and 89, and acts on the ratchet wheel 113 for moving the combs in the widening direction. It therefore must act on the downward stroke of the actuator, since the spindles at the right end of the machine, Fig. 42, turn in the clockwise direction, viewed from their outer ends, when widening and those at the left end, Fig. 10, turn counterclockwise when widening. Said special control arrangement includes a link 157 one end of which is pivotally connected to the pawl 109 intermediate its ends. Said link is pivoted at its other end to an arm or lever 158 fixed to a shaft 159 pivotally mounted on transverse portions 161 of frame 55 and running longitudinally along the rear of the narrowing head 87 so that, when the shaft 159 turns, it swings the back-racking pawl 109 on its pivot. A spring 162, best shown in Fig. 16, between the lower end of arm 158 and a fixed point on the actuator 97 biases the back-racking pawl toward active position but it is held inactive except at desired times by said special control arrangement. The end stops 91 are carried by the large nut 96

which is directly engaged by the end stop spindle 89 and a rearward projection 163 on said nut is connected to a bent arm 164 having an enlargement surrounding and sliding on said shaft 159, the bend in said arm causing it to project upwardly a little to the rear of the center line of the shaft. A bracket 165 fixed on the shaft 159, which may be integral with the arm 158 thereon for moving the back-racking pawl 109, carries a square bar 166 which lies above and parallel to shaft 159 and carries several cam pieces 167, 168 and 169 best shown perhaps in Figs. 11 and 12 above the shaft, placed at different points longitudinally of the shaft and adapted to contact in turn the upper end of said bent arm 164 as the end stop nut 96 is moved by its spindle 89, thereby turning the shaft 159 to turn lever 158 and moving and holding the back-racking pawl so that it cannot engage the widening ratchet 113 on the comb moving spindle 88 so long as arm 164 is in engagement with either of cams 167, 168 or 169. In the portion of its path in which said arm is out of contact with any cam piece on the bar 166, the spring 162 swings the back-racking pawl 109 into position in which it is active, so that it engages its ratchet 113 on the down stroke of the actuator 97 as shown in Fig. 16, the shaft 159 then swinging counterclockwise so that the top forward edge of the said bent arm 164 lies between two cam pieces, Fig. 37.

Cams like said cam pieces 167, 168 and 169 have commonly been rigidly fixed to the bracket 165 or bar 166 so that, once set, the positions and portions of the path of the end stops at and within which the back-racking pawl would act on the spindle 88 would be determined and would be the same whichever way the stops 91 were being moved.

According to my invention, however, means are provided whereby the back-racking pawls 109 may be employed over a greater portion of the path of each set of end stops 91 when the end stops are moving in the widening direction than when they are moving in the narrowing direction. For this purpose, I have provided means whereby the central one, 168, of each group of cam pieces for contacting the upper end of bent arm such as said arm 164, while fixed against movement longitudinally of the control shaft 159, is movable at right angles to said shaft. As shown, the movable cam piece 168 is so mounted that it may be moved out of the path of bent arm 164, preferably by being raised above the level of the upper end of said arm. Further, the cam member 168 is shown as formed of several parts, the active face of cam member 168 being in the form of a U-shaped piece 171, Figs. 16 and 18, which is inverted when in use so that the bridge or connecting portion of the U is at the top. Said bridge portion is provided with several holes 172 through which, when the device is assembled, extend vertical pins 173 for guiding part 171 during its vertical movements. Pins 173 are fixed at their lower ends to a block 174 which is embraced by and fits the inner surfaces of the legs of U-shaped member 171, parts 171 and 174 having a sliding fit for vertical movement of part 171. U-shaped part 171 is, however, guided or held against movement in the direction longitudinally of the machine, the shaft 159 and the bar 166 on the one side by a rectangular plate-like portion 175 which projects laterally beyond the edges of portion 174. Portion 175 is shown as integral with part 174, but I do not limit myself to

this. On the other side of part 174, U-shaped part 171 is prevented from movement longitudinally of bar 166 by a slotted portion 176 which is preferably but not necessarily integral with part 174 and which projects laterally therefrom toward the front and the rear of the machine so as to guide the edges of part 171 on one side thereof. Part 176 is shown slotted so that it can be bolted to bar 166 as shown to hold it and parts 174 and 175 in adjusted position on the bar 166. Further, parts 174 and 175 are shown as drilled parallel to bar 166 to receive a pin or pins 177 the ends of which are shown projecting from parts 174 and 175. A headed post 178 is shown as fixed to the bridge portion of part 171 centrally thereof, and extends therefrom parallel to the legs of U-shaped portion 171. Springs 179 extending between said pin 177 and a split pin 181 through the head of said post 178 parallel to pins 177 and act as means to draw part 171 downward on pins 173 to hold it in the position shown in Figs. 11 and 14 unless moved upwardly against the tension of springs 179 by some other means. For so drawing part 171 against the tension of springs 179, I have shown a means which suitably comprises a block 182 fixed to the bracket 165 on the control shaft 159 and having a rod 183 fixed thereto and extending at right angles or vertically upward therefrom. Near its outer or upper end, said rod 183 has a rod or spindle 184 fixed thereto by a bracket 185 so as to extend parallel to the control shaft. On said spindle 184 is a wheel 186 over which runs a flexible connector or chain 187 one end of which is attached to the pin 181 in the post 178 of said movable cam piece 171 and the other end of which is attached to a fixed point shown as a block 188 on the end of a rod 189 the other end of which is secured in a part fixed to the machine frame. So long as the upper end of arm 164 is in contact with one of cams 167, 168 and 169, rod 183 and wheel 186 are held toward the right as viewed in Fig. 10 so that the chain 187 is slack. Transversely movable cam 168 therefore remains down in operative position, being drawn and held down by springs 179 and by gravity. When, however, arm 164 runs off of piece 171 as 164 traverses in the narrowing direction, spring 162 swings shaft 159 so that wheel 186 tightens chain 187 and lifts piece 171 as shown in Fig. 16. Consequently, at the start of a blank the end stops being set for knitting the initial widest portion of the fabric or stocking, the upper end of the bent control arm 164 is in contact with the cam piece 167 nearest the outer end of the control shaft. As knitting proceeds with narrowing from time to time, the bent arm runs off first the outer cam piece 167 but catches on piece 168 before leaving piece 167 and, after moving off of cam 168, it drops into a recess or gap 192, Figs. 33 to 41, between pieces 168 and 169 thereby permitting spring 162 to swing shaft 159 and causing chain 187 to pull movable cam piece 168 up out of the way of bent arm 164. This occurs at the time during the knitting of the stocking fabric within my invention, and shown in Figs. 1 and 2, at which it becomes necessary to widen the fabric. The pattern chain 64 thereupon operates on the means for shifting the camshaft 62 to cause the shaft to shift to the right and on the means to turn the pivoted cam 108 on the point comb spindle 88 to throw the narrowing pawls out of action and the widening pawls into action. Just after the cam 108 on the spindle has been so turned, the actuator is raised and lowered. The

upstroke of the actuator would then be expected to turn the point comb spindle two needles in the widening direction but, as the back-racking pawl is now in position to act on the downstroke, this would cause the point spindle to be turned three needles in one complete reciprocation of the actuator and would therefore throw the point comb spindle out of proper relationship to the end stop spindle. Further and of even more importance, for fabric reasons, it is desired to move the point combs only one needle in the widening direction for the purpose of transferring outwardly the end or edge loops of the fabric. This occurs while the needles are in their lower position. In order to prevent the point comb spindle 88 from turning more than one needle on the upstroke of the actuator, I have provided said thin plate cam 152 on the point comb spindle 88 and mounted outside the widening ratchet 113 which can be set to delay the engagement of the widening ratchet wheel 113 by its pawl 105 on the upstroke of the actuator, so that the pawl moves the ratchet wheel and widening spindle only one needle. One or more loops at each selavage edge, depending on the setting of the combs 78, are therefore transferred outwardly one needle at each operation.

As the same time that the actuator 97 first turns the point comb spindle one needle, on the upstroke of the actuator, it also turns the end stop spindle two needles in the widening direction. The point combs are thereby thrown one needle out of their original relation to the end stops. However, the back-racking pawl 109 being active, it then turns the point comb spindle 88 one needle on the downstroke of the actuator, thereby turning the point comb spindle two needles per complete reciprocation of the actuator and maintaining the relation between the end stop and the point comb spindles as originally set. The movable cam piece 168 having been pulled out of the path of the bent arm 164 by the flexible connector, the back-racking pawl is retained in position to act on the comb carrying spindle while the widening movements of the end stops carry the bent arm in the widening direction through the entire width of the movable cam piece 168 in the direction longitudinally of the shaft 159. The widening process can therefore be continued to the extent necessary without interference due to a cam piece on the bracket 165 acting on the bent arm 164. When, however, the bent arm strikes the cam 167, the one against which it rested at the start, the cam and bracket are moved so as to turn the shaft 159 and to swing the arm 158 and link 157 to throw the back-racking pawl 109 out of action. The buttons for acting on rod 146 are then omitted from the pattern chain to cause the plate cam 108 to throw the widening pawls out of action and to permit the narrowing pawls to engage the narrowing ratchet wheels on the 60 threaded spindles whenever the actuator is reciprocated.

The bent arm 164 having moved in the widening direction into contact with the first cam piece, cam 167, on the control shaft 159, the shaft is turned enough to cause the flexible connector 167 to go slack and to permit the movable part 171 to drop down onto the part 174 which is in line with the bracket, because the rear face of movable cam 168 is relieved slightly so that it does not quite touch the bent arm 164 when the bent arm is in contact with the cam piece 167. The fabric may then be narrowed, when the proper time arrives to finish the heel and afterward to 75

produce the usual foot and toe narrowings at the usual time.

As perhaps is best shown in Figs. 11, 12 and 13, cams 167 and 169 are also adjustably attached to bar 166 and the means shown for so attaching cams 167 and 169 to the bar comprises bolts extending through slots in the cams. Further, cams 167 and 169 are bevelled as shown at 191 and 194, respectively, on their adjacent corners so that arm 164 may push them to one side as it moves in one direction and then the other longitudinally of bar 166, arm 164 being complementally bevelled to further facilitate the action of the arm on cams 167 and 169. Also, the 15 rear leg of slotted portion 176 is preferably recessed as shown at 193 (Fig. 12) to receive the bevelled portion 194 of cam 169.

The fabric and method

20 The loop structure produced by my improved mechanism affords a non-ravelling selvage along the widened zone and the end stops may be stepped out two needles in the widening direction as often as every third course of loops. If it is not desired that the angle of the selvage of the widened section to the line of knitting be as abrupt as afforded by widening every third course, widening every fourth, fifth or larger numbered course may be adopted. The action of the machine in producing the locked selvage edge shown in Figs. 6, 25 7 and 8 will now be explained. The end stop and comb spindles, as is well known, are operated only when the main camshaft 62 has been shifted longitudinally out of the knitting position into what is commonly known as the narrowing position in 30 which no yarn is laid to the needles. In a narrowing or widening cycle, the actuator rises to turn the spindles only after the point combs have picked up the loops, in other words only after the needles have progressed a goodly percentage of a 35 cycle from their starting position. At the time the end stops are moved out two needles by their spindles when transferring out the edge loops as in the first course *a* in Fig. 7 to be widened, they drag the yarn carriers out an equal distance at the same time, because the present standard narrowing head includes means for latching the yarn carrier bars to the head while the friction box mechanism is stationary. As the outward 40 movement of the head and yarn carriers comes so late in the cycle, the beards of the needles have passed below the level at which the yarn is laid by the time said outward movement occurs. On its upstroke, the end needle then passes rearwardly of the yarn so that the yarn passing to the yarn carrier finger is on the back or non-bearded side of any needle or needles outside the one holding the transferred loop on the side toward the carrier, the carrier being placed a distance therefrom equal to twice the distance between two adjacent needles by the outward movement of the end stop and yarn fingers: At the beginning of the next transverse movement of the yarn carrier, therefore, the yarn is then carried in front of or along the bearded sides of the needles, thereby forming a loop around a needle outside the one added by loop transference on the side at which the carrier stopped. The needle next outside the end needle, the one holding the end loop, therefore catches yarn in the next course after the narrowing heads have been moved out but there is no loop in the previous course to draw it through and the loop formed on such outside needle therefore almost always drops out and has no effect on the fabric as is 45 50 55 60 65 70 75

shown in course *b* of Fig. 7. The result is, as shown in Figs. 6, 7 and 8, that only one loop is added at each side of the fabric at the first operation of transferring outward the edge loops. As, however, the end stops were moved out two needles at the time the edge loops were transferred out one needle, the yarn finger comes to rest at the end of course *b* a needle distance farther from the needle holding the end loop than usual as above pointed out. Similarly, when the edge loops are transferred out a second time, due to the fact that any loops drop out which may have formed initially on needles outside the ones to which the original edge loops were transferred, the yarn finger again moves out two needles while the edge loops are moved out only one needle, so that, when the yarn carrier finger begins to lay yarn for the course immediately following the second one in which edge loops were transferred outwardly, the finger is two needles farther from the needle holding the end loop than usual, three needles in all, and the bight of free yarn is correspondingly longer. It results from this that at least one sinker loop adds itself to the selvage in the course following the second outward transfer of the edge loops, as appeared at *e* in Fig. 7. In the course following the one in which loop *e* was formed a sinker loop *f* appeared on the opposite side of the fabric from loop *e*. In the same course in which loop *f* appeared, the one following loop *e*, a full needle loop *g* appeared, on the same side of the fabric as sinker loop *e*. Also, a needle loop *h* built on at the same side of the fabric as loop *f*, being formed initially in the course next after loop *f*, although having been caught up by some irregularity into the second course from the one containing loop *f*. After the course of loop *g*, the combs are given an additional step after each transferring operation in Fig. 7, but in courses *a* and *c* only one loop is transferred at each edge.

The sequence according to which loops were built on to the selvages, in addition to those added by transferring the edge loops, was so similar in Fig. 8 to that followed in Fig. 7 that the operations of transferring and adding or building on loops in Fig. 8 will not be described, except rather generally as follows:

In Fig. 8, the points of the combs pick up the two outer loops at each side of the fabric and transfer them outward one needle in both courses *a* and *c*, the second movement of the combs per transfer, the movement caused by the back-racking pawls *109*, beginning just after the second transferring action, that in course *c*. Sinker loops *e* and *f* and needle loops *g* and *h* then build on and the line of widening marks remains constantly parallel to the selvage and is spaced two needle loops therefrom throughout.

As to Fig. 6, however, it is to be noted that a different sequence was followed than in Figs. 7 and 8. In Fig. 6, as the yarn finger laid the yarn for the course *c*, it travelled from left to right, and a needle loop *x*, with accompanying sinker loop *u*, was added to the right edge of the fabric in addition to the loop added by the outward transferring operation. In the same course as loop *x*, a sinker loop *e* was added at the left edge of the fabric. Loops *g* and *h* were then built on as in Figs. 7 and 8. This sequence was repeated in Fig. 6 following the third outward transferring operation, but due to causes not clear, in the second course from said third operation. In Fig. 6, three loops are transferred out at each edge in course *a*, and two in course *c*.

It will be seen that after the second transferring operation two loops were added to the fabric at each side thereof at each such operation, so that, in each of Figs. 6, 7 and 8 the selvage was then maintained a uniform distance from the yarn finger, due to a second one needle movement of the combs after the edge loops were transferred, such second movement of the combs beginning just after the first transfer in Fig. 6, the third transfer in Fig. 7 and the second transfer in Fig. 8. It will be seen further that, following the second outward transferring operation, usually three courses were required to add the maximum number of loops added to the fabric per widening operation, namely, two at each edge of the fabric or four in all. While, therefore, I consider it necessary to employ at least three courses per "repeat," I may include four or more courses per "repeat" because an average of one-half or less added loops per course per edge is sufficient to widen the fabric as rapidly as needed to produce a satisfactory heel, depending on the form adopted for the foot portion of the blank. As shown in Figs. 6, 7 and 8, the second and third outward transfers are each three courses from the next preceding transfer, while the fourth and, presumably, succeeding outward transfers are each four courses from the next preceding transfers.

In Figs. 32 to 40 inclusive, I have shown the positions of moving arm *164* relative to the cams *167*, *168* and *169* at different points in the manufacture of the stocking blank *B*, the said cams controlling, in large measure, the widening and narrowing operations.

At the beginning of the welt *W*, the forward face of arm *164* is in contact with the rear face of cam *167*. During the operations of making the knee narrowings *K* and calf or leg narrowing *C* the upper end of arm *164* moves along the rear faces of cams *167* and *168*. Just as the machine completes the last fashion mark of the leg narrowings *C*, arm *164* slides off the cam *168* and the shaft *159* at the left end of the machine swings counterclockwise as viewed from the left, so that arm *164* lies partly in the recess *192* between cams *168* and *169* as shown in Fig. 35, thereby placing back-racking pawl *109* in active position. At the next and several subsequent operations of the narrowing machine, the pattern chain *64* operates the mechanism *129* so that widening results to produce lace openings along the upper edge of the heel. Because shaft *159* has swung as just stated, the cam piece *171* has been raised out of the way of arm *164* by the flexible member or chain *181* and the chain *181* then continues to hold piece *171* in elevated position so that arm *164* passes beneath cam piece *168* as shown in Figs. 13 and 15 and until arm *164* strikes cam *167* as shown in Fig. 39. The arm *164* then swings shaft *159* clockwise to put pawl *109* out of commission until the time for widening the next blank, while the buttons for operating mechanism *129*, and thereby cam *108*, are omitted from chain *64* until the time for widening the next blank. Each operation of the actuator *97* therefore then produces a narrowing effect until the end of blank *B*. The shaft *159* having been again swung by arm *164*, cam piece *168* drops into its active position because its rear face is slightly relieved compared to cam *167* and the subsequent heel and toe narrowing operations proceed as indicated in Figs. 2 and 32 to produce the line of fashion marks *T* along the lower edge of the heel and the line of fashion marks *U* along the edge of the toe. It will be noted that arm *164* will pass out of con-

tact with cam 168 at the next to the last point or fashion mark in the narrowings forming lines T of fashion marks, such point being the one at which the end stops are in the same positions as at the lower ends of the leg narrowings and one in which arm 164 lies intermediate cams 168 and 169. In making the next and last fashion marks in line T, arm 164 will pass up onto cam 169, so that the back-racking pawl 109 will not affect subsequent narrowings such as those forming the line of fashion marks U of the toe narrowings, but the arm 164 being between cams 168 and 169 during the time between the formation of the next to the last and the last fashion marks in line T, the back-racking pawl 109 acts in such time, causing the last fashion mark in line T to be off-set one needle wale from the line formed by the remainder of the fashion marks T. However, this slight off-set is noticeable only on close inspection and is not shown.

In order, however, that the V arrangement of lace openings can be made in the high heel of a stocking such as A, a further modification of the narrowing head mechanism is required. As shown in Fig. 2, the selvages in the ankle and high heel sections of the blank B are walewise and parallel while the lines of the lace openings are inclined outwardly. Such an arrangement in the stocking requires that the narrowing and lace points or combs on which they are mounted be moved outwardly while the end stops remain stationary. Therefore, I have provided means whereby the end stop spindle 89 is not turned at certain times when the comb moving spindle 88 is turned to move the combs away from each other. The means provided and disclosed for such purpose is best shown in Figs. 21 to 31, inclusive, and comprises a lever 201 pivoted at its lower end to a fixed bracket arm 202. A spring 203 is connected between a point on lever 201 somewhat above its pivot and a fixed pin 204 on the end frame 56 of the machine and serves to turn lever 201 in the counterclockwise direction as viewed in Figs. 26 and 27 so far as permitted by a hook-shaped link 205 pivoted at or near its front end to an arm 206 at or near the lower end of said arm. Said arm 206 is fixed at or near its upper end to an oscillatable collar 207 journaled on a rod or axle 208 fixed to the machine frame. A spring 209, Fig. 10, connected between a hook 211 at the forward end of fixed bracket member 202 and a pin on link 205 applies a tension to link 205 and the lower end of arm 206 in the rearward direction. Collar 207, however, has a limited oscillatory motion on rod 208 so that it may draw link 205 forward to the position shown in Fig. 26 in which lever 201 is nearly upright. In this position, while it has no effect on the widening pawl 106 for the end stop spindle 89 so long as cam 168 holds the racking pawls 105 and 106 out of action as shown in Fig. 26, as soon as the pattern chain swings cam 169 into the position shown in Fig. 27, pawl 105 is enabled to rack spindle 88, but link 205 is so far forward that rear edge of a hook-shaped cut-out 212 in link 205 engages a bolt 213 on lever 201 and holds lever 201 clockwise and forwardly so that an edge 214 of a cut-away portion of lever 201 engages a pin 215 on widening pawl 105 to hold the pawl forwardly and clockwise so that the pawl 106 cannot engage its ratchet wheel to turn the end stop spindle 89.

A means is provided for controlling and turning collar 207 and thereby lever 201 at the desired times to so prevent pawl 106 from actuating spin-

dle 89 even though the other means for controlling pawl 106 would permit this pawl to rack the spindle when actuated. As shown best, perhaps, in Fig. 21, collar 207 and arm 206 are connected to a second collar 216 on rod or axle 208 by means of a web 217, collars 207 and 216 being held against movement longitudinally of rod 208 by collars 218 and 219 one fixed to the rod 208 and the other fixed to the frame of the machine. 10 The web 217 is extended inwardly from the inner collar 216 in the form of an arm 221, shown as having a rectangular section, the inner end of which has mounted thereon a cam plate 222 shown as covering the upper and rear faces of arm 221 and adjustable lengthwise of the arm 221 by means of a screw and slot connection 223, Figs. 24 and 25. Slidably mounted on rod 208 is a collar 224 connected by an arm or web 225 (Fig. 22) with one of the nuts 94 on the comb operating spindle 88 so that collar 224 moves along rod 208 as the nut 94 is moved by the spindle. Fixed to arm 225 and collar 224 and depending therefrom is a block 226 having a recessed contact face 227 adapted and arranged 15 to contact the rear face of the vertical portion of the cam plate 222 when nut 94 brings face 227 into transverse alignment with plate 222. When face 227 moves into contact with cam plate 222 as in Fig. 25, the plate 222 and thereby arm 221 and the lower end of arm 206 are pushed forwardly, thereby also drawing link 205 forwardly and moving arm or lever 201 clockwise from the position shown in Fig. 10 and Fig. 26 to that shown in Fig. 27 in which arm 201 20 contacts pin 215. Arm 201 thereby prevents widening pawl 106 from turning spindle 89 even though pawl 105 is in operative relation to spindle 88. The parts being in the position shown in Fig. 30, therefore, an outwardly inclined line P 25 of lace openings will be formed by the transfer points while the average position of the selvage edges will be substantially unaffected. It will be understood that the manufacture of single unit fabrics as herein described requires a greater overall traverse of the nuts 94 than is provided in the standard legger. In the machine shown, this effect is obtained by making the nuts 94 of only about half the length previously employed.

50 The relationship of the control block 226 and cam plate 222 for controlling widening pawl 106 to the control arm 164 and cams 167, 168 and 169 for controlling the back-racking pawl 109 and the relationship of both said controls to the knitting of the blank B is shown somewhat diagrammatically in Figs. 28 to 40, inclusive. In Fig. 32, there is shown one-half of the single unit blank B of Fig. 2 having the usual knee narrowings, leg narrowings and toe narrowings, but having also a heel pocket piece formed by widening and a line P of lace openings beginning in the high heel, and running parallel to the widened edge of the heel pocket piece so as to form a V in conjunction with a similar line of lace openings on the other side of the blank. The positions of the end stop nut 96, collar 224, cam 227, and combs 78 at the beginning of the knee narrowings are shown in Fig. 28, the corresponding positions of arm 164 and block 226 being shown in Fig. 33. Here the narrowing pawls are in position to operate upon operation of the narrowing machine, back-racking pawls 109 each being held out of action by a cam 167 and the widening pawls being held out of action by the pattern controlled cam 168. As knitting pro-

ceeds, members 164 and 226 are moved incidental to the formation of the knee narrowings and the leg or calf narrowings along from the position shown in Fig. 33 first to that shown in Fig. 34 and then to that shown in Fig. 35. At this point in the formation of blank B the combs 78 have moved to the position shown in Fig. 29, collar 224 and block 226 depending therefrom overlapping on cam 222. As shown in Fig. 35, arm 164 has moved into the recess between cam member 168 and cam 169 and block 226 has moved into contact with cam 222. As the arm 164 lies in the recess between cams 168 and 169, the back-racking pawls 109 are then free to act, but they do not have opportunity to make an effect on the fabric between the lower end of the fashion marks for the leg narrowings and the high heel because the next operation of the narrowing machine during the manufacture of the blank B then comes at the upper end of the high heel R. Further, by the time arm 164 has reached the position shown in Fig. 35, block 226 has made contact with cam 222 so as to throw lever 201 into the position shown in Fig. 27. After the ankle section has been knitted, the line of lace openings begins in the upper portion of the high heel, that is the stocking blank shown in Fig. 32. Therefore, at the upper end of the high heel shown in Fig. 32, the pattern chain shifts the cam 108 to shift the pawls for the spindles 88 and 89 to change the effect of the up and down motions of the actuator 97 from one moving the point combs toward each other to one moving the point combs away from each other. Further, it being desired that the lines of lace marks begin farther inward from the selvage than the lower end of the leg or calf narrowings, the point combs are shifted inward by turning spindle 88 by hand so that combs 78 occupy the positions shown in Fig. 30 and the lace marks in line P begin at a wale inside the wale of the last fashion mark of the leg narrowings. The same hand operation that moves the point combs inward and toward each other preparatory to beginning the lines of lace openings also moves the block 226 farther along on cam plate 222, so that, at the beginning of line P, arm 164 and block 226 are in the relative position shown in Fig. 36 in which block 226 is a greater distance on the cam 222 than shown in Fig. 35. The arm 164 being in said recess and block 226 being on cam 222 the widening pawl 106 for the end-stop spindle 89 is out of commission, but the back-racking pawl 109 and the widening pawl 105 are in commission. Therefore, the spindle 89 and the arm 164 remain stationary and the selvage runs parallel to the wales so long as block 226 remains on cam 222, but the line P inclines rather sharply toward the selvage because the comb operating spindle 88 is turned two needles per revolution, one needle by the pawl 105 and one needle by the back-racking pawl 109. As knitting proceeds, however, in the formation of the high heel with the formation of the line of lace openings therein, the spindle 88 is turned in the widening direction, thereby moving the block 226 to the left from the position shown in Fig. 36. When the course at the lower end of the high heel R has been formed the block 226 drops off the cam 222, thereby permitting pawl 106 to act. The parts then have the relative position shown in Figs. 31 and 37 in which both spindles 88 and 89 will move in the widening direction to both widen the fabric and continue the lace openings. The back-racking pawl will then continue

to act while the parts pass through the positions shown in Fig. 38 in which cam 168 is lifted and in which heel portions H are formed and until arm 164 again passes onto cam 167 as shown in Fig. 39. Therefore, the lace openings in the portion of line P along side the widened edge of the heel are not only parallel to the selvage but are aligned with the lace openings in the high heel, so that there is no angle in the line F of lace openings, the lace openings making the same angle with the wales in the high heel as in the heel tabs. The pattern chain thereupon reverses the action of the pawls again by shifting cam 108 so that up and down movements of the actuator 97 again causes narrowing movements of the point combs and points. Arm 164 having moved into operative contact with cam 167 as shown in Fig. 39, the cam 168 is permitted to drop and the back-racking pawl will be put out of operation until the arm 164 has passed off cam 168 in the narrowing direction. Of course, during narrowing, the pawl 106 is held out of operation by cam 108, so that the position of block 226 is immaterial.

At the end of the widening movements for making the heel pocket pieces H, the point comb spindle 88 is preferably again turned by hand in the narrowing direction so that the beginning of the line of fashion marks T formed by the sole or gusset narrowings shall be spaced inward somewhat more from the selvage than the lower end of the line of lace openings. After the sole or gusset narrowings T, the spindles 88 and 89 are inactive until the line of fashion marks U are formed in the toe, the arm 164 and block 226 remaining respectively on cam 169 and cam 222 throughout the toe narrowing operations as indicated by Fig. 40.

In Figs. 1 and 2, the lace openings are not taken into the seam, but it is assumed that this will be the case as to the fabrics shown in Figs. 6, 7 and 8, in which the lace openings begin at the widened sections. When making fabric shown in detail in Figs. 6, 7 and 8 and diagrammatically in Figs. 4 and 5, the block 226 is unnecessary. As stated hereinabove, it is desirable that the first lace opening or two in Figs. 7 be as close as possible to the selvage because otherwise the operative who makes the seam is apt to leave such first opening or two out of the seam. This arrangement is shown diagrammatically in Fig. 5. In making the rows of fashion marks C, as shown in Fig. 5, the narrowing operations are continued several times after the arm 164 runs off cam 168 in the narrowing direction, thereby throwing pawl 109 into action and making some fashion marks D which are offset in walewise relation to the fashion marks C and causing arm 164 to move into contact with cam 169 as shown in Fig. 41. Spindle 88 is then turned by hand to adjust the point combs during the making of the ankle section of blank X shown in Fig. 5 so that the inner points of the combs are above the needles having the end loops thereon. The cam 169 is set initially as shown in Fig. 41 so that the parts 164 and 169 remain in contact and pawl 109 is kept out of action during the first two widening operations. This is necessary because the first widening operation is performed when the points pick up only one loop at each selvage edge and move it outward, as indicated at J in Fig. 5. As only one loop is formed at each edge on the first loop that has been transferred outward, the back-racking pawl 109, if active at this time, would move the inner lace points out beyond the needles

holding the end loops and cause the lace openings to be omitted. As it is desired that there be at least two loops between most of the lace openings of line S of Fig. 5, and the selvages, the arm 164 must be placed originally to stay on the cam 169 until after the second widening to produce said desired result. As two loops per selvage are added at or soon after the second widening, the selvage gains a loop at this time on the lace openings. However, after the second widening operation, two loops begin to be added at each side of the fabric per widening operation, so that, at the third widening, there is a needle loop outside the one last transferred. Therefore the back-racking pawl 109 at each end of the machine needs then to operate to maintain the points and point combs in proper relation to the end stops and the pawls 109 begin to operate at the third widening shown in Fig. 7.

However, if the point combs are set so that the points pick up two loops at each edge of the fabric at the first transferring operation, as shown in Fig. 8, the arm 164 is in overlapping relation with cam 169 only during the first widening operation and the lever 201 and its associated parts 222 and 226 can continue to be omitted.

In forming the widened fabric shown in Fig. 6, the arm 164 lies intermediate cam pieces 168 and 169 at the first widening, but the point comb spindle 88 is set by hand so that each comb picks up three loops at the first widening operation. The back-racking pawl 109 being active because of the position of arm 164, the point comb at each side moves out two needles on the first widening operation while only one loop is added at each side. At the second widening operation, therefore, only two loops are picked up and moved outwardly by the point combs, after which two loops are added per operation and the lace openings remain two loops or wales from the edges. If, however, it is desired that the remaining lace openings shall be three needle loops from the selvages, the cam 169 must be set by hand initially so that arm 164 moves off cam piece 169 immediately after the second widening.

In the formation of the fabric shown diagrammatically in Figs. 3 and 4, the lace openings in line Y of blank Z of Fig. 4 for producing the stocking Q are maintained the same distance from the selvage throughout the line Y. In this case, the arm 164 is arranged to run off cam 168 at the end of fashion mark C of the leg narrowings and the pattern chain throws cam 108 to move the racking pawls of the spindles 88 and 89 to widening position as soon as the widened sections of the heel are begun. The line of lace openings Y is parallel to the widened edge of the heel section throughout because the lace openings occur in all of the courses in which widening occurred and the back-racking pawls 109 were active throughout. The lace openings, however, occurring in no course not in the widened heel section, the lever 201, cam 222 and block 226 are unnecessary. As in other instances mentioned, the point combs are shifted by hand both before and after the formation of lines Y of lace openings. In making all the forms of fabric shown, the second one needle step of the point combs in widening may be produced by the back-racking pawl but the invention is not limited to this in all cases.

In the manner described, I am able to widen knitted fabric to produce a satisfactory heel for a single unit stocking without extensive modi-

fications of the standard narrowing head as supplied to standard leggers and can therefore make a diamond point toe in a single unit stocking by modifying cam 169 if desired, although such are not shown. The selvages along the widened heel sections, moreover, give no trouble, being of locked character, and the openings formed by transferring certain loops outwardly can be arranged so that they enhance the appearance and add to the elasticity of the finished stocking which has the known desirable features of single unit construction as to the uniformity of shade between the foot and instep portions of the stocking and the absence of a line at the instep.

If desired, however, the line of lace marks produced by the widening steps can be arranged so that it may be readily taken into the seam.

Of course, the improvements specifically shown and described by which I obtain the above results, can be changed and modified in various ways without departing from the invention herein disclosed and hereinafter claimed.

I claim as my invention:

1. In a straight knitting machine, the combination with threaded end stop and comb moving spindles of means for turning said end stop spindles adapted to turn them simultaneously enough in one step in the widening direction to move the end stops at both ends of the machine twice the distance between adjacent needles and adapted to turn the comb spindles to move the combs in the widening direction a distance equal to the movement of the end stops but in two steps, and means for turning said end stop spindles and said comb spindles in the narrowing direction to move the end stops and combs to narrow the fabric.

2. In a flat knitting machine, in combination, a point comb spindle, pawl and ratchet means adapted to move said spindle in two needle steps in the widening direction, a device arranged to be adjusted to change the action of said means to one needle steps, a pawl acting at times to move said spindle in one needle steps in the widening direction, and automatic means to throw said second mentioned pawl into action.

3. In a knitting machine, the combination of point combs, spindles therefor, end stops for yarn carrier bars and spindles therefor, pawls for said spindles, a reciprocating actuator for said pawls, an automatic control means for a pawl acting to turn a point comb spindle to move its comb one needle in the widening direction on a stroke of the actuator in one direction, said control means adapted to hold said pawl out of action for a definite portion of the length of travel of said stops when the stop spindle is being turned in the narrowing direction and to permit said pawl to act in said portion of the travel of the stops when the stop spindle is being turned in the widening direction.

4. In a knitting machine having point combs, spindles therefor, thread bar stops, and spindles therefor, the combination with said comb moving and stop moving spindles of means comprising pawls for turning said spindles in either the narrowing or the widening direction, said means including two pawls for turning said point comb spindle in the widening direction, and reciprocating actuator for said last two pawls arranged to move said comb spindle by one pawl a one needle distance in the widening direction as the actuator moves in one direction and to move the spindle by the other pawl a one needle distance in the widening direction as the actuator moves in the other direction.

5. In a knitting machine having a pattern means, point combs, spindles therefor, end stops for yarn carrier bars and spindles therefor, the combination as set forth in claim 2 together with two forms of automatic control means, one form acting in response to the pattern means and the other form acting in response to the position of the end stops, to cause the widening pawls to act on the point comb spindle.

6. In a flat knitting machine, in combination, a point comb spindle, a nut for said spindle, a pawl for moving said spindle in two needle steps in the widening direction, a pawl for moving said spindle in one needle steps in the widening direction, a common ratchet for said pawls, a device adjustable to reduce the length of the steps caused by said first pawl from two needles to one needle, and an automatic control means for said second pawl arranged to maintain it out of action for a greater portion of the travel of said nut in one direction than in the other.

7. In a flat knitting machine, in combination, an end stop spindle having a nut thereon, a point comb spindle, means for turning said stop spindle to move its nut in steps of two needles in either the narrowing or the widening direction, a pawl for turning the point comb spindle in the widening direction, an arm on said nut, a cam piece arranged to be in contact with said arm when the arm is moving in the narrowing direction, connections between said cam piece and said pawl for holding the pawl out of action when said arm is in contact with the cam piece, and a means arranged to be operated by a portion of said connections for moving said cam piece out of the path of said arm when the arm is moving in the widening direction.

8. In a flat knitting machine, in combination, a point comb spindle, a nut for said spindle, means for turning said spindle to move said nut in the narrowing direction, a ratchet wheel for turning said spindle to move said nut in the widening direction, a pawl adjustable to move said ratchet to turn said spindle to move said nut in either one needle or two needle steps in the widening direction, a second pawl for turning said ratchet to move said nut in one needle steps in the widening direction, and a control for said second pawl acting automatically to hold it out of action for a portion only of the path of said nut but for a greater portion of such path when the net movement of the nut is in the narrowing direction than when the net movement of the nut is in the widening direction.

9. In a flat knitting machine having a back-racking pawl, a control arrangement for said pawl comprising a pivoted shaft, a bar parallel to said shaft and bracketed thereto, an end stop nut having an arm fixed to travel therewith and extending adjacent said bar, a cam piece mounted on said bar and movable at right angles thereto, said arm contacting said cam piece in a certain part of its path to turn said shaft, a spring tending to turn said shaft oppositely to the way in which it is turned by said arm, a connection to said cam piece, parts connected to said shaft and arranged to act on said connection to draw said cam piece out of the path of said arm when said arm has moved out of contact with said cam piece to permit said spring to turn said shaft, whereby the direction of movement of the end stop nut may be reversed and said arm moved past said cam piece in the opposite direction without acting on the shaft.

10. In a flat knitting machine having a back-

racking pawl, a control means for said pawl comprising a cam, an end stop nut having an arm connected thereto and movable therewith, a pivoted shaft having a connection with said pawl, a cam piece supported from said shaft adapted to be contacted by said arm to turn said shaft and adapted to be moved transversely of said shaft out of the path of said arm, and means released by the action of said arm in passing out of contact with said cam piece, after having passed along its entire surface, for moving the cam piece out of the path of said arm to permit it to reverse its movement without effect on the shaft during its movement in the reverse direction throughout the portion of the path of the arm in which it contacted said piece.

11. In a flat knitting machine, in combination, a point comb spindle, a nut for said spindle, means for turning said spindle to move said nut in the narrowing direction, a ratchet wheel for turning said spindle to move said nut in the widening direction, a pawl adjustable to move said ratchet to turn said spindle to move said nut in either one or two needle steps in the widening direction, a second pawl for turning said ratchet to move said nut in one needle steps in the widening direction, a movable cam piece, connections between said cam piece and said second pawl, a part moving in the narrowing direction at each narrowing operation and in the widening direction at each widening operation and acting on said movable cam piece to cause said connections to prevent said second pawl from acting during certain of the narrowing operations, a flexible member connecting said cam piece to a fixed point, a rigid arm connected to a portion of said connections and moved thereby at the completion of said certain narrowing operations to move said cam piece into position in which said second pawl operates said ratchet one needle during widening operations.

12. In a full-fashioned knitting machine having point comb spindles and end stop spindles and racking means therefor adapted to be set to turn said spindles in one direction or the other, the combination with said spindles and a back-racking pawl for acting on said comb spindle and means to actuate said pawl to turn said comb spindle in the widening direction, means adapted to maintain said pawl out of action a portion of the time irrespective of whether said racking means are set for narrowing or widening the fabric, and means adapted to prevent at times effective action of said racking means for turning the end stop spindle in the widening direction.

13. In a full-fashioned knitting machine having a point comb, a point comb spindle, an end stop spindle, and racking means for said spindles adapted to turn said spindles in either the widening or narrowing direction as desired, the combination with said spindles and means of a back-racking pawl to turn said comb spindle in the widening direction, a means for at times preventing the racking of said end stop spindle in the widening direction, and means for operating said back-racking pawl while said preventing means is active to permit the points on the combs to form a line of lace openings inclined toward the selvege, said last means also operating said back-racking pawl while the end stop spindles are active in the widening direction to permit the formation of lace openings aligned with said line and parallel to the fabric selvages.

14. In a full-fashioned knitting machine, the combination of an end stop spindle, a point comb

spindle, an actuator arranged for up and down movement, pawls pivotally mounted on said actuator and adapted when permitted to turn said comb spindle two needles at each upward movement of said actuator, a cam adjustable to a position in which said pawl is permitted to move said point spindle two needles and to another one in which said pawl is permitted to move said point comb spindle only one needle, and a second pawl adapted when permitted to turn said point comb spindle one needle on a downward movement of said actuator in the same direction as the spindle is turned by said first pawl, so that said point comb spindle may be turned in the widening direction two needles per reciprocation of said actuator in either one step or two steps.

15. In a full-fashioned knitting machine, the combination of an end stop spindle, a point comb spindle, means for racking said spindles in both the narrowing and the widening directions, a piece arranged to be moved by said point comb spindle longitudinally of the spindle, and means including said piece for preventing the racking of said end stop spindle in the widening directions when said piece is in certain portions of its path.

16. In a full-fashioned knitting machine, the combination as set forth in claim 26 and in which the pawl means includes a back-racking pawl of the pull-back type together with an arm arranged to be moved by the end stop spindle longitudinally of itself, and means including said arm for preventing the racking of the comb spindle in the widening direction by said back-racking pawl when said arm is in certain portions of its path.

17. In a flat knitting machine, in combination, a threaded point comb spindle, a main camshaft, means for turning said spindle including a movable actuator operated from said camshaft and pawl means receiving motion from said actuator and adapted to turn said spindle enough in one step in the widening direction to move the combs a distance equal to twice that between next adjacent needles, a device adapted when in use to restrict the one step action of said pawl means in the widening direction so as to move the combs only the distance between two next adjacent needles, and automatic means adapted when said device is in use to cause said pawl means to turn said spindle enough to cause a second one needle step of the combs in the widening direction.

18. In a flat knitting machine, in combination, a threaded point comb spindle, a threaded end stop spindle, a main camshaft, means for turning said spindles including a movable actuator operated from said camshaft and pawling means receiving motion from said actuator and adapted to turn said spindles enough in one step in the widening direction to move the end stops and the combs a distance equal to twice that between next adjacent needles, a device adapted when in use to restrict the one step action of the pawling means for said comb spindle in the widening direction so as to move the combs only the distance between two next adjacent needles, and pattern controlled means for causing said actuator to cause said pawling means to move the combs a second step in the widening direction of the distance between two adjacent needles before another movement of the end stop spindle.

19. In a full-fashioned knitting machine including point combs and end stops, and stepping means therefor, the combination of means

including nuts for stepping the point combs outwardly and means controlled by the position of the nuts for the point comb stepping means to step the points outwardly at the same time preventing action by the end stop stepping means to produce a line of lace openings inclined outwardly toward the selvage.

20. In a knitting machine having point combs, spindles therefor, thread bar stops and spindles therefor, the combination with said combs, stops and spindles of means comprising pawls for turning said spindles in either the widening or the narrowing direction, said means arranged to turn said comb moving spindle to move the combs two needles in the widening direction for a widening operation of said stop spindle but in two successive steps and in the second of which the points are not engaged with the loops of the fabric.

21. In a knitting machine having point combs, moving spindles therefor, thread bar stops and moving spindles therefor, the combination with said comb moving and stop moving spindles of means comprising actuators moved at times first up and then down and pawling means operated thereby for turning said spindles in either the widening or the narrowing direction and including pawls adapted to act on the up stroke of said actuator to turn the comb spindles and pawls adapted to act on the down stroke of said actuators to turn the comb spindles, said means arranged to turn said stop moving spindles to move the stops two needles in the widening direction at an up stroke of said actuators, the stop moving spindles remaining stationary on the next following down stroke of the actuators, to turn said comb moving spindles by said first pawls to move the combs one needle in the widening direction on said up stroke of the actuators and to turn said comb moving spindles by said second pawls to move the combs one needle in the widening direction on the down-stroke next following said up stroke.

22. The method of widening fabric during the power operation of a full-fashion knitting machine during the knitting thereof comprising transferring outwardly by points a group of loops including the edge loop from the needles on which they were formed to next adjacent needles, increasing the travel of the yarn to include two additional needles beyond the original position of said edge loop and moving the points further outwardly the distance between two next adjacent needles while free of loops, all between the laying of yarn for one course and the laying of yarn for the next course.

23. The method of widening fabric during the power operation of a full-fashion knitting machine during the knitting thereof comprising transferring outwardly by points a group of loops including the edge loops from the needles on which they were formed to next adjacent needles, moving the points further outwardly the distance between two next adjacent needles while free of loops, and increasing the travel of the yarn within the period covering said two movements of the points to include two additional needles beyond the original position of said edge loop.

24. The method of widening fabric being knitted during the power operation of a full-fashion knitting machine on a bank of machine needles by means of a point comb and a yarn carrier comprising transferring outwardly by points a group of loops including the edge loop from the needles on which they were formed to next ad-

5 adjacent needles, moving the point comb outwardly while free of loops an additional distance equal to that between two next adjacent needles, and increasing the travel of the yarn carrier within the period covering said movements of the comb to include two additional needles beyond the original position of said edge loop.

25. In a full-fashioned knitting machine having a main camshaft, a point comb and a spindle for moving said comb, a pawl for turning said spindle in the widening direction, means rendering said pawl active to turn the spindle a distance moving the comb one needle distance in said direction, a pull-back pawl for turning said spindle in the widening direction, and means rendering said pull-back pawl active to turn said spindle a distance moving the comb an additional one needle distance in said direction, the turning of said spindle by said pull-back pawl following the turning of the spindle by said widening pawl within one revolution of the main cam-shaft.

26. In a knitting machine having point combs and thread bar stops and spindles therefor, the combination with said combs, stops and spindles of means comprising pawls for turning said spindles in either the widening or narrowing direction, said means arranged to turn said spindles to move the stops two needles in the widening direction at one operation and to move the combs two needles in the widening direction for a widening operation of said stops but in two successive steps.

27. In a full-fashioned knitting machine having point combs and thread bar stops and spindles therefor, the combination with said comb and stop spindles of racking means therefor comprising pawls and pawl controlling cams for turning said spindles in either the widening or the narrowing direction, said means adapted to turn said spindles to move the stops two needles in the narrowing direction at one operation and to move said combs two needles in the narrowing direction for a narrowing operation of said stops, and adapted to turn said spindles to move said stops two needles in the widening direction and to move said combs two needles in the widening direction in two steps between successive operations of the said stops.

28. The method of narrowing or widening fabric as desired during the power operation of a full-fashioned knitting machine the steps of widening comprising transferring outwardly by points a group of loops including the edge loop from the needles on which they were formed to next adjacent needles, increasing the travel of the yarn in one step to include two additional needles beyond the original position of said edge loop, and moving the points further outwardly the distance between two next adjacent needles intermediate im-

5 mediately successive increases in the travel of the yarn, and the steps of narrowing comprising transferring inwardly a plurality of loops including the edge loop and decreasing the travel of the yarn.

29. In a full-fashioned knitting machine, power actuated fabric fashioning means including end stops, point combs, stepping means acting to move said end stops and point combs inwardly or outwardly to narrow or widen the fabric as required while maintaining the selvages parallel to the fashion marks or lace openings as the case may be, and mechanism operating in conjunction with said stepping means to prevent the movement of said end stops in an outward direction during a period in which the stepping means moves outward the point combs whereby to produce lines of lace marks inclined outwardly toward the selvages going in the direction of knitting.

30. In a full-fashioned knitting machine, power actuated fabric fashioning means including end stops, point combs, stepping means including spindles and nuts on said spindles and acting to move said end stops and point combs inwardly or outwardly to narrow or widen the fabric as required while maintaining the selvages parallel to the fashion marks or lace openings as the case may be, and mechanism responsive to the position of the nut on one of said spindles and operating to prevent the stepping means from moving outward the end stops in a period in which the stepping means moves outward the point combs to thereby form lines of lace marks along the inner edge of a transferred group of loops and inclined outwardly toward the selvages going in the direction of knitting.

RICHARD E. SCHLETTNER.
